CLAIM

The ornamental design for a combined container and cap, as shown and described.

DESCRIPTION

FIG. 1 is a perspective view of a combined container and cap showing our new design;

FIG. 2 is a side elevation view thereof, the opposite side being a mirror image;

FIG. 3 is a front elevation view thereof, the rear view being identical;

FIG. 4 is a top plan view thereof;

FIG. 5 is a bottom plan view thereof;

FIG. 6 is a perspective view of a second alternate embodiment;

FIG. 7 is a side elevation view thereof, the opposite side being a mirror image;

FIG. 8 is a front elevation view thereof, the rear view being identical;

FIG. 9 is a top plan view thereof; and,

FIG. 10 is a bottom plan view thereof.
